(57) **CLAIM**

The ornamental design for a dragging device for moving game animal, as shown and described.

DESCRIPTION

FIG. 1 is a perspective view of our design;

FIG. 2 is a top view of our design;

FIG. 3 is a bottom view of our design;

FIG. 4 is a front view of our design; and,

FIG. 5 is a side view of our design.

The features shown in broken lines, if any, are shown for illustrative purpose only and form no part of the claimed design.
